MULTIPOSITION ROTARY SWITCH

Alan P. Sullivan, Elizabeth, N. J., assignor to
 Cities Service Oil Company, New York, N. Y.,
 a corporation of Pennsylvania

Application September 15, 1944, Serial No. 554,224

11 Claims. (Cl. 200—6)

1

This invention relates to electrical circuit switching means, and more particularly to improvements in multi-position rotary switches.

The principal object of the invention is to provide a rotary switch which may have two circuit closing positions, or many, and in which the contacts may be arranged in single pole or multi-pole disposition, depending only upon the number of substantially identical sets of parts which are disposed in each deck, and the number of decks of parts which are pancaked together in the final assembly.

It is a further object of the invention to provide a multi-position rotary switch having its circuit-making and breaking contacts enclosed within a housing which is formed by the contact-supporting and separating insulators, and which serves to exclude dust and dirt, and to minimize the effect of rapidly changing atmospheric conditions upon the contacts.

Another object of the invention is to provide a switch of this kind in which the fixed contacts extend through the housing in such fashion that their outer ends are readily accessible for permanent interconnection among themselves or to the conductors of an electrical circuit of which they are to form parts.

It is a further object of the invention to provide a deck switch which may be made in smaller sizes than any of the conventional devices of this kind having a comparable number of contact points that are now available, and the parts of which may be inexpensively manufactured and cheaply assembled in small manufacturing lots.

The foregoing and other objects of the invention, as well as its various features, will be better understood from a consideration of the following description in the light of the accompanying drawings, in which

Fig. 1 is a perspective view of a series of parts which may be assembled together to provide a single deck switch;

Fig. 2 is a side view of a switch assembled from the parts of Fig. 1;

Fig. 3 is a sectional view taken on the line 3—3 of Fig. 2;

Fig. 4 is a sectional view taken on the line 4—4 of Fig. 3;

Fig. 5 is a perspective view, on a much enlarged scale, of a pair of the fixed contacts of the switch of Figs. 2 to 4 inclusive;

Fig. 6 is a side view, partly in section, of a modified form of the switch of Figs. 1 to 5;

Fig. 7 is a sectional view taken on the line 55

2

1—7 of Fig. 6, with certain parts broken away better to show underlying ones;

Fig. 8 is a perspective view of a series of parts which may be assembled to provide a two-deck switch;

Fig. 9 is a side view, largely in section, of a switch assembled from the parts of Fig. 8, and Fig. 10 is a cross-sectional view taken on the lines 10—10 of Fig. 9.

10 The device which is illustrated in Figs. 1 to 5 inclusive is what is generally known in the art as a single deck switch having three contact positions. Referring to these figures, it will be seen that the switch comprises three pairs of fixed contacts 18 and 19 which are disposed radially on the ends of a cylindrical supporting member 20, with the inner ends of each pair aligned in overlapping spaced relation, (Figs. 3 and 4) and with the outer ends of the contacts projecting beyond the outside surface of the supporting block so as to be readily accessible for connection to an electrical circuit. In the finished switch these contacts are preferably clamped in fixed position by a pair of similar insulating spacers 21 and 22, the end plates 23 and 24, and suitable bolts or rivets 25. The movable contact of the device consists of a silver pin 26 which is mounted in an insulating drum 27 in such a position that it may be caused to bridge 15 any one of the pairs of fixed contacts 18, 19, to close an electrical circuit of which they are parts, by the rotation of a drum supporting shaft 28 in its bearings in the end plates.

It is generally preferable in a device of this kind to provide detent means which serve to hold the movable contact in bridging relation with any selected pair of fixed contacts. This function is served in the illustrated switch by a spring arm 29 which is secured to the rear 20 end of drum 27 and shaft 28 by a bolt 30, and which has a rib 31 in its forward end, overlying and pressed against the outer edge of the rear end plate 24, so that it may lie in any one of the three notches 32 which are formed in the end plate in positions corresponding to those of the three pairs of fixed contacts.

This switch is adapted to be mounted on a panel in unconventional fashion. Thus its front end plate 23 is provided with a stud 34 of such length that it may pass through an opening in the supporting panel, and is threaded to receive a conventional locking nut 35 as shown in Fig. 2.

The fixed contact supporting member 20 (Fig. 1) preferably takes the form of a short cylinder of insulating material having four shallow ra-

dial slots 36 in each of its end faces, with the slots aligned to receive the fixed contacts 18 and 19. The depth of the slots at the outer edge of the support is about equal to the thickness of the fixed contacts, and preferably they slope inwardly at a slight angle (Fig. 4). This ring may be made of any insulating material which lends itself to easy working, and which has sufficiently good electric insulating qualities and adequate mechanical strength. In the illustrated device it comprises nothing more than a short section of phenolic resin tubing having three holes 37 drilled therein to receive the bolts 25, and having the contact receiving slots 36 milled in its end faces.

The fixed contacts are made of phosphor bronze or other suitable spring metal which preferably has one side silver-coated for better electrical conduction. Fixed contact 18 comprises a tab of the spring material having its outer end turned back upon itself to form a hook 38 which serves to receive the end of an electrical conductor in the finished device, and opposite edges turned back slightly at its inner end, as indicated at 39 (Fig. 5), so that the silvered side of the contact is of slightly dished cross section. Between these end portions, however, the contact is substantially flat so that it may lie snugly in one of the slots 36 of supporting member 20.

The second fixed contact 19 is preferably somewhat longer than the first one, and has a hole 40 formed in its flat outer end to facilitate the attachment of an electrical conductor. The inner end of this contact is also turned up slightly along its edges as indicated at 41, in a direction away from the silvered side, precisely as was the end of the first contact.

The rotating drum 27 serves primarily to support the movable contact in properly spaced relation to the fixed contacts 18, 19, and to insulate it from the shaft and other parts. It may accordingly be made of any suitable insulating material such as phenolic resin. As here shown, the drum has a body portion 42 (Fig. 4) with an upstanding peripheral flange 43 which is of such thickness as to be capable of passing between the inner ends of the spaced pairs of fixed contacts 18, 19. The movable contact pin 26 is preferably made of pure silver, and extends crosswise of this flange, being secured in position either by friction alone or more permanently by having its opposite ends slightly upset. A second peripheral flange 44 is formed on the body of the drum in such position that it may abut against the rear end plate 24 in the finished device. Other constructional details of this drum and of various other parts of the switch assembly will be readily apparent from Figs. 1 to 5, and will be considered in somewhat greater detail hereinafter.

In assembling the switch, the drum 27 is fitted on shaft 28 with its rear end flush with the rear end of the shaft. The rear end plate 24 is then applied over the end of the drum until its inner face abuts against flange 44, and these several parts are held in assembled relation by a collar 45, which also serves to confine the inner end of the detent spring 30, and by bolt 29.

In the next stage of the assembly, front end plate 23, insulating spacer 21, fixed contact support 20, and insulating spacer 22, are sandwiched together in that order as shown in Figs. 1 to 4, and are fitted over drum 27 and shaft 28 with the holes 46, 47, 37, and 48 in these several elements aligned with each other and with the holes 49 in the rear end plate 24. The latter holes are

preferably threaded to receive the threaded ends of bolts 25 which of course serve to hold the parts in assembled relation.

At this stage of the assembly the parts should be held together rather loosely, with bolts 25 not turned down tight, in order to allow for insertion of the fixed contacts 18, 19 in the slots 36 of the fixed contact support 20. In carrying out this operation the contacts are inserted in the slots with their silvered sides facing each other, and are pushed in until their inner ends abut body 42 of the drum 27. When this has been done the contacts are backed off slightly, to just the extent which is necessary to allow for a free turn of the drum. The assembly of the several parts being now complete, the bolts 25 may be turned down tight to clamp the contacts in the positions thus established.

The fixed contact support 20 and the two insulating spacers 21, 22 are so proportioned as to thickness that upon assembly in the foregoing fashion the fixed contacts 18, 19 necessarily overlie the opposite sides of flange 43 of drum 27, and are so disposed that movable contact pin 26 is adapted to wipe between them and spring them apart slightly to make good electrical contact with them. In this connection, it will be evident that the turned back edges 39, 41 of the fixed contacts are directed away from each other in the finished unit (Figs. 4 and 5) so that these edges are spaced slightly farther apart than their center sections. This arrangement assures that movable contact pin 26 will sweep between the inner ends of fixed contacts in the operation of the switch and will not catch against their edges.

It will also be noted (Figs. 2 and 4) that the hooked ends 38 of fixed contacts 18 face toward supporting ring 20 so that each of them forms a small pocket into which the end of an electrical conductor may readily be inserted and soldered in place. The outer ends of the other fixed contacts 19, which were purposely made somewhat longer than contacts 18, extend well beyond the outer surface of supporting ring 20 so that they are readily accessible for the soldering on of electrical conductors without interference with fixed contacts 18.

It is a feature of this switch (Fig. 4) that the inner ends of the fixed contacts 18, 19, and of course the entire movable contact 26, lie wholly within a closed housing which is formed by the support 20, spacers 21, 22, and the two end plates 23 and 24. While the housing is not gas proof, the openings around the shaft are so small that rapid changes in atmospheric conditions are not quickly transmitted to the interior of the switch, and little dust can enter through them. The switch is therefore substantially dust-proof, and little or no trouble is occasioned by the entry of dirt and other matter to foul the contact points.

It will readily be evident that the structure is not limited to a three-position switch of the kind heretofore described. If fewer contacts are wanted, then all that is needed is a fixed contact supporting member 20 having correspondingly fewer contact receiving slots 36. On the other hand, where more than three circuit closing positions are required, it is only necessary to use a supporting ring having an appropriately larger number of radial slots and a corresponding number of pairs of fixed contacts, in assembling the switch. Such a switch is illustrated in Figs. 6 and 7, where it will be seen that the ring 20a has slots for receiving nine pairs of fixed contacts, and that the rear plate 24a is provided

with nine detent notches **32a**, each of which is aligned with one of the pairs of fixed contacts, **18a**, **19a**. The spacer rings **21a**, **22a**, movable contact **26a**, drum **27a**, and other parts of this switch are, however, identical with the like parts of Figs. 1 to 5 inclusive, and the assembly of these parts may be carried out in the general manner heretofore described.

The switches which have been described above each include but a single fixed contact support, and are what are known as "single deck" assemblies. In many cases more than one deck of fixed contacts is required in order to provide for complicated circuit connections. The switch of the present invention lends itself readily to multi-decking, of which one example is shown in Figs. 8 to 10 inclusive. In this unit two fixed contact members **20b** are employed, each having three sets of contact receiving slots **36b**, with the rings insulated one from another by a spacer **21b**. This spacer, and that between the first fixed contact support and front end plate **23b** may be identical with spacer **21** of Fig. 1; and spacer **22b**, which separates the second fixed contact support from the rear end plate **24b** may be identical with spacer **22** of Fig. 1.

Drum **27b** is generally similar to that of Figs. 1 to 4, except insofar as it is provided with an additional movable contact **26b**, and in that the two movable contact pins are mounted in lugs **50** which extend only part of the way around body **42b**, and that a similar lug **51** has been substituted for the abutment flange **44** of Fig. 1. It will be perfectly evident, however, that peripheral flanges, such as **43** and **44** (Fig. 1), may be employed instead of the lugs where that is desired; and contrariwise, that lugs comparable to **50** and **51** may be employed in the switch of Figs. 1 to 5, in lieu of the continuous flanges **43** and **44** there shown.

In the assembled device (Fig. 9) entire reliance is not placed upon lug **51** to hold the shaft against axial movement. Part of this function is performed by a pin **52**, which is secured to shaft **28b** and abuts against the forward end of the stud portion **34b** of front plate **23b**. This pin serves the further function of limiting rotation of the shaft by contact with abutments **53** which is formed by cutting away part of the end of stud **34b** as is shown in Figs. 8 and 9. If desired, of course, the abutment may be omitted, and pin **60** extended so that it projects completely through supporting shaft, in which case the switch may be shifted between any two sets of contacts by the rotation of the shaft in either direction. Obviously, too, lug **51** may be replaced by a flange comparable to **44** of Fig. 1 in which case pin **53** may be omitted.

It will be apparent to those skilled in the art that the switch may be assembled from common parts having a single deck or two decks as shown, or, that one or more additional decks may be included, and that the drum may be provided with additional movable contact pins **26** to match the added decks. Again, it will be evident that the number of pairs of fixed contacts which are included in any deck may be more or fewer than those shown; and that both the fixed and movable contacts may be inter-connected in accordance with conventional switching practice to provide almost any combination with may be required for complete circuit control. Further, it will be appreciated that the detent spring **30** may be omitted entirely, or that some other form of detent may be employed.

In all of the foregoing switches it will be noted that an insulating spacer **21**, **22** has been employed between each end plate **25**, **26** and the adjacent fixed contact supporting member **23**. Where the switch is to be made up in small manufacturing lots this practice has some advantage in that the end plates may be simple screw machine parts and the spacers may be cut from standard forms of insulated tubing. If desired, however, these spacers may be formed integrally with the end plates, which can be synthetic resin castings or die cast metal parts. In the former case, of course, the end plates constitute their own insulation while in the latter, the metal end plates may be insulated from the fixed contacts by any conventional means.

Since certain changes may be made in the illustrated and preferred embodiments of the invention, it is intended that the foregoing shall be construed in a descriptive, rather than a limited sense.

I claim:

1. A multi-position switch comprising a cylindrical supporting member of insulating material having radially directed slots formed in its end faces with each slot in one face lying opposite a slot in the other face; a plurality of fixed contacts, each disposed in one of said slots, said contacts being arranged in opposing pairs with their inner ends projecting from the inner cylindrical wall of said supporting member and lying in overlapping spaced relation, and with their outer ends adapted for connection to an electrical circuit; a rotatable shaft extending centrally through said supporting member; journal means for said shaft; a movable contact carried by said shaft, said movable contact being so disposed that it may be caused by rotation of said shaft to bridge any one of said pairs of fixed contacts; and means for holding said contacts in assembled relation.

2. A multi-position rotary switch comprising a fixed contact supporting member of generally cylindrical proportions, said member having a plurality of radially directed slots formed in substantially aligned relation in its opposite end surfaces; a plurality of fixed contact elements, each disposed in one of said slots and projecting into the bore of said member, the inner ends of the fixed contact elements at one end of said member lying in overlapping spaced relation to the corresponding portions of the contact elements located at the other end thereof; a pair of end plates covering the ends of said member and being adapted to clamp said contacts in fixed relation; means for securing said end plates and supporting member together; a shaft extending through the bore of said member, and being journaled in said end plates; and a movable contact element carried by said shaft, said movable contact being so disposed that it may be caused by rotation of said shaft to bridge any opposing pair of fixed contacts to close an electrical circuit of which they are parts.

3. A multi-position rotary switch according to claim 2 characterized in that said supporting member and said end plates form a substantially closed housing which is adapted to exclude dust and dirt from the inner ends of said fixed contacts.

4. A multi-position rotary switch according to claim 2 characterized in that the outer ends of said fixed contacts project from the outer cylindrical wall of said member for connection to an electrical circuit; and in that said supporting

member and said end plates form a substantially closed housing which is adapted to exclude dust and dirt from the inner ends of said fixed contacts.

5. A multi-position rotary switch according to claim 2 further characterized by the provision of a drum secured to said shaft and confined within the bore of said member by said end plates; and in that said movable contact element comprises a pin which is secured to said drum with its ends adapted to sweep between and in contact with the inner ends of opposing ones of said fixed contact elements.

6. A rotary switch comprising a plurality of substantially identical fixed contact supporting members, of generally cylindrical proportions, each said member having radially directed slots formed in substantially aligned relation in its opposite end faces; a plurality of fixed contact elements each disposed in a slot in one of said members with the inner ends of the elements at one end of each member lying in overlapping spaced relation to the inner ends of the elements at the other end of that member; said members being disposed in aligned relation, an insulating spacer of generally cylindrical proportions separating said members; a pair of end plates covering the ends of said members and being adapted to clamp said contact elements in fixed relation; means for securing said end plates, said members and said spacer together; a shaft extending through the bore of said members and spacer; and being journaled in said end plates; and a plurality of movable contacts carried by said shaft, there being one such contact for each supporting member; each movable contact being so disposed with respect to one of said supporting members that it may be caused by a rotation of said shaft to bridge any opposing pair of fixed contacts carried by that member.

7. A rotary switch according to claim 6 characterized in that said fixed contact supporting members, said spacer and said end plates form a substantially closed housing which is adapted to exclude dust and dirt from the inner ends of said fixed contacts.

8. A fixed contact assembly for a rotary switch comprising a contact supporting member of generally cylindrical proportions, said member having radially directed slots formed in aligned relation in its opposite end faces; a plurality of fixed contact elements, each disposed in one of said slots with its inner end projecting into the bore of said member and lying in overlapping spaced relation to the end of the contact in the opposing slot; said contacts being of a thickness which is approximately equal to the depth of the shallowest parts of said slots; end plates cov-

ering the ends of said member; and means for securing said end plates and member together and for clamping said contacts in fixed position; each of said fixed contacts being substantially flat between its ends and being adapted to be inserted in said slots after said member and end plates have been assembled.

9. A fixed contact assembly for a rotary switch comprising a contact supporting member of generally cylindrical proportions, said member having radially directed slots formed in aligned relation in its opposite end surfaces; a pair of insulating spacers of generally cylindrical proportions covering the end surfaces of said member; a pair of end plates; means for securing said member, spacers and end plates together in aligned relation; and a plurality of fixed contact elements, said elements being substantially flat between their ends and of a thickness which approximately equals the minimum depth of said slots, said elements being adapted to be inserted in said slots after the assembly of said member, spacers, and said end plates.

10. A multi-position switch comprising a cylindrical supporting member of insulating material; a plurality of fixed contacts disposed in arcuately spaced relation upon the opposite ends of said supporting member, said contacts being arranged radially in opposing pairs with the inner ends of each pair projecting from the inner cylindrical wall of said member and lying in overlapped spaced-apart relation, and with their outer ends adapted for connection to an electrical circuit; a rotatable shaft extending centrally through said supporting member; journal means for said shaft; a movable contact carried by said shaft and so disposed that it may be caused by rotation of said shaft to bridge any one of said pairs of fixed contacts; and means for holding said contacts in assembled relation.

11. A fixed contact assembly for a rotary switch comprising a contact-supporting member of generally cylindrical proportions; an insulating spacer of generally cylindrical proportions covering an end surface of said member, the abutting end surfaces of said spacers and said supporting member defining a plurality of radially directed and arcuately spaced slots; a pair of end plates; means for securing said member, spacer, and end plates together in aligned relation; and a plurality of fixed contact elements, said elements being substantially flat between their ends and of a thickness which approximately equals the minimum depth of said slots, said elements being adapted to be inserted in said slots after the assembly of said member spacers and said end plates.

ALAN P. SULLIVAN.
